UNITED STATES PATENT OFFICE.

JAMES J. WOOD, OF FORT WAYNE, INDIANA.

DESIGN FOR A FRAME FOR ELECTRIC DYNAMOS.

SPECIFICATION forming part of Design No. 21,270, dated December 29, 1891.

Application filed December 3, 1891. Serial No. 413,940. Term of patent 14 years.

To all whom it may concern:

Be it known that I, JAMES J. WOOD, a citizen of the United States, residing in Fort Wayne, in the county of Allen and State of Indiana, have invented and produced a certain new and original Design for Frames of Dynamo-Electric Machines and Electromotors, of which the following is a specification.

My new design for the frame or field-magnet of a dynamo-electric machine or electromotor is shown in the accompanying drawings, wherein—

Figure 1 is a perspective view thereof. Fig. 2 is an end elevation thereof. Fig. 3 is a side elevation thereof. Fig. 4 is a plan thereof.

According to my new design the frame consists of two opposite body portions A A, having wide-spreading legs a a at their lower portions and horizontally-projecting arms b b 20 at their upper portions and the two body portions united by a flattened cylinder B. The body portions A A are made thick and massive, with their lower outer portions at c c, with plane surfaces in the middle, and round- 25 ing at the sides, and these plane surfaces in extending upwardly merge into a cylindrical portion d, which curves toward the middle at the top, the cylindrical surfaces of the two opposite body portions approaching each 30 other at the top at the same level. The inner sides of the body portions are cylindri- cally concaved at e e. The sides of the body

portions are rounded at f f, and at the lower portion thereof are swelled outwardly at g g, corresponding with but being larger than 35 the end outlines of the cylinder B. The arms b b are shaped with tapering ribs h h along the top and bottom and the outer sides, thereby forming between them a channel i. The ends of the arms slightly approach each 40 other and are connected by cross-pieces C C, formed with their middle portions of cylindrical or barrel shape at D D.

The bottom of the body portions merges into the legs a a by gradual curves, and these 45 legs are formed with a convexed outward curvature, as shown at j j in Fig. 3, and terminate in flat feet k k, which rest on straight rectangular bases E E. These bases are flat on the sides and top and rounded at their 50 ends l l.

I claim as new—

The design for the frame of a dynamo-electric machine or electromotor shown in the accompanying drawings, the same consisting 55 of the shape thereof, as shown and described.

In witness whereof I have hereunto signed my name in the presence of two subscribing witnesses.

JAMES J. WOOD.

Witnesses:

C. S. KNIGHT,
T. H. DASCOMB.
